UNITED STATES PATENT OFFICE

2,047,511

LOOM HARNESS

John Jacob Kaufmann, Elkins Park, Pa., assignor
to Steel Heddle Manufacturing Company, Phil-
adelphia, Pa., a corporation of Pennsylvania

Application October 27, 1934, Serial No. 750,250

15 Claims. (Cl. 139—92)

This invention relates to loom harness, and relates more particularly to a novel construction of heddle frame and the heddles used in connection therewith.

5 The present invention will be found particularly useful where it is desired to insert the warp through the heddle by means of the warp drawing machines which are now in use. For such purpose it is essential that the heddles be permitted entire freedom of movement upon their supporting rods, without being obstructed by the supporting hooks which are commonly used in loom harness frames of the ordinary types.

10 Heretofore it has been customary, when warp drawing machines were used for drawing in the warp in loom harness in which flat steel heddles were used, to perform such operations apart from the heddle frames, because the hooks or other devices used in the frames for supporting the heddle rods intermediate their ends formed obstructions which interfered with the manipulations of the warp drawing machines, and no satisfactory heddle frame has heretofore been devised in which the heddles were free to move past the 15 heddle rod supporting devices.

15 It has also been well known that streaks or the so-called "reed marks" are sometimes caused in the cloth, particularly in the weaving of fabrics of high count, by reason of lack of freedom 20 of the heddles on their supporting rods, and the slide hooks heretofore devised to overcome this difficulty, have never proved entirely satisfactory.

The principal object, therefore, of the present 25 invention is to provide a heddle frame, and heddles mounted therein, which are so constructed and arranged that the heddles may have complete freedom of movement upon their supporting rods, notwithstanding that the heddle supporting rods are supported in the frame at various places 30 intermediate their ends.

40 A further object of the invention is to provide a loom harness frame of the character aforesaid, in which the heddle supporting rods may, if desired, be taken out of the frame without 45 removing the heddles therefrom.

A further object of the invention is to provide 50 a novel form of heddle which is particularly adaptable for use in a heddle frame of the character aforesaid, but which also has certain inherent advantages, as will be hereinafter pointed out.

55 A further object of the invention is to provide improved means, in a harness frame, for supporting the heddle rods intermediate their ends.

The nature and characteristic features of the

invention will be more readily understood from the following description, taken in connection with the accompanying drawings forming part hereof, in which:

Figure 1 is a front elevation of a loom harness 5 frame, and heddles mounted therein, embodying the main features of the present invention;

Fig. 2 is a face view of one of the heddles shown in Fig. 1;

Fig. 3 is a similar view of another of the 10 heddles shown in Fig. 1;

Fig. 4 is a similar view of a modified form of heddle, which may be employed when the warp is entered by hand instead of by means of a warp drawing machine;

Fig. 5 is an enlarged sectional view taken approximately on the line 5—5 of Fig. 1;

Fig. 6 is a fragmentary elevational view, enlarged, of a portion of the structure, illustrating principally the preferred means for supporting 20 the heddle rods intermediate their ends;

Fig. 7 is a fragmentary perspective view of a portion of one of the heddle rods, and a portion of one of the devices for supporting said rods intermediate their ends shown in operative relationship therewith; and—

Fig. 8 is a similar perspective view illustrating a modified form of heddle supporting rod, in which the device for supporting the same intermediate its ends is connected directly thereto.

It will, of course, be understood that the description and drawings herein contained are illustrative merely, and that various modifications and changes may be made in the structure disclosed without departing from the spirit of the 35 invention.

Referring to the drawings, the heddle frame proper may be of any preferred construction. For example, as shown, the same comprises top and bottom rails 10, connected at their ends by 40 end struts 11. The heddle supporting rods 12 are of peculiar construction, being formed from strips of relatively thin metal bent to a flattened C shape, thereby to provide internal grooves 13 and a longitudinally extending slot 14 45 on one side of each heddle rod.

The ends of the heddle rods 12 extend through slots in the end struts 11 in the usual manner. Each of the projecting end portions of each heddle rod is provided with an aperture 15 which 50 is engaged by the hooked end of a spring retaining member 16. Various other forms of retaining means at the ends of the heddle rods may be used if desired, although it has been found that spring members such as are shown in my pre- 55

vious Letters Patent No. 1,780,786 are satisfactory for the present purpose.

The means for supporting the heddle rods 12 intermediate their ends is shown in enlarged detail in Figs. 5, 6 and 7 of the drawings and comprises essentially a plate member 17 positioned in the interior of the heddle rod 12, and means for supporting said plate member from the rail of the frame. The plate member 17 is 10 preferably mounted on the lower end of a metallic bracket member 18, which extends outwardly from said plate member, as at 18, through the slot 14 in the side of the heddle rod, and thence toward the rail 10, where it is integrally joined to the lower end of a bolt member 20 which is positioned in said rail.

The bolt member 20 preferably extends entirely through the rail 10, and has its outer end threaded, as at 21. Upon this threaded end 21 there is mounted a nut 22 provided with an inner flange 23. The flange 23 of the nut 22 is positioned between the inner face of a plate 24 and the outer face of a washer 25. The washer 25 is seated in a suitably shaped counterbore in the rail 10, and the plate 24 is attached to the rail 10 by means of wood screws 26. The arrangement is such that the frictional tension on the flange 23 may be varied by adjustment of the screws 26.

It will be noted that, by the foregoing arrangement, the plate member 17, which is carried by the extending bracket portion 18 of the bolt member 20, may be adjusted with respect to the rail 10 by turning the nut 22 in one direction or the other. It will of course be understood that other means for adjustably supporting the plate member 17, with respect to the rail 10, may be employed if desired.

The preferred form of heddle for use in connection with the present invention is shown in Figs. 2 and 3 of the drawings. The heddles 30 there shown are preferably made from thin flat strips of metal of a width corresponding to the widest portion of the heddle. The central portion 31 of the heddle 30 is preferably left the full width of the strip, as is also each end portion 32 thereof, but the parts of the heddle between the central portion and the respective end portions are sheared down to a considerably narrower width, as at 33, for a purpose to be presently explained.

The central portion 31 of the heddle is provided with the usual punched warp eye 34, the shanks of which may, if desired, be formed in bowed conformation out of the main plane of the heddle proper. The central portion 31 is left the full width of the strip for a greater length than would be required merely for the warp eye, in order to permit the punching above the warp eye of a keyhole slot 35, which is provided when the warp is to be entered by means of a warp drawing machine. Certain of the heddles have the narrow portion of the keyhole slot 35 extending downwardly, while the alternate heddles have the keyhole slot punched with the narrow portion extending upwardly, as shown respectively in Figs. 2 and 3 of the drawings.

The unpunched part 36 of the central portion 31 of the heddle below the warp eye 34, which is left the full width of the strip, is provided for engagement by that part of the mechanism of the warp drawing machine which is used for twisting the heddle to enable the needle of the warp drawing machine to pass freely through

Each of the end portions 32 of each of the heddles shown in Figs. 2 and 3 of the drawings (which, as hereinbefore mentioned, is left the full width of the strip from which the heddle is formed) is punched out to provide a slot 37 for mounting the heddles on the rods 12, and one side portion thereof is cut away, as at 38, substantially midway of the extension of the slot 37, so that when the heddles are slid sidewise on the rods 12, they will pass freely without being obstructed by the outwardly extending portion 19 of the bracket portion 18 of the bolt member 20.

By this arrangement, there are provided, at each end portion 32 of the heddle, a solid strip 39 which extends over the face of the solid side 15 of the heddle rod 12, and fingers 40 on the other side of said heddle rod, which engage the faces of the lip portions of the rod.

It should here be noted that the slot 37 provided at each end 32 of the heddle is of a length 20 greater than the width of the heddle rod 12, so as to permit the heddles to have the usual and necessary slight up and down movement on the heddle rods, which permits the heddles to accommodate themselves to the positions of the 25 warp ends controlled thereby. The width of the opening 38 in one side of each end portion 32 of the heddle is such that in the uppermost and lowermost positions of the heddles on the rods 12, the fingers 40 will clear the outwardly extending portion 19 of the bracket portion 18 of the bolt member 20.

It should also be noted that the opening 38 at one side of one end portion of the heddle is preferably on the opposite side from the opening 38 at the other end 32 of the heddle, the heddle rods 12 being correspondingly mounted in the frame, with the slots 14 thereof disposed on opposite faces of the frame.

When loom harness constructed as hereinbefore described is employed, and it is desired to draw in the warp, it will not be necessary to remove the heddles from the frame, but the frame may be mounted directly in the warp drawing machine. When so mounted, the selector of the 45 warp drawing machine, operating through the keyhole slots 35 provided in the heddles, will cause the heddles to be separated one by one, and brought to the proper position for the insertion of the needle through the warp eye 34 of each heddle. 50

As the warp drawing machines are usually provided with means for twisting the central portion of the heddle, thereby to present the widest possible opening of the warp eye to the needle, the heddle is preferably left the full width, as at 36, 55 for a certain distance below the warp eye 34, for engagement by the twisting mechanism of the warp drawing machine.

It should also be noted that, by reason of the reduction in the width of the heddles in the portions 33 thereof which extend from the relatively wider central portion 31 to the end portions 32, the twisting of the central portion of the heddle may be accomplished with greater facility and without placing undue strain on the end portions 65 which are mounted on the rods 12.

This is particularly important when heddles of the type shown in Figs. 2 and 3 of the drawings are employed, as by reason of the cutting away of the central part of one of the side portions of each end 32 of the heddle, it is necessary to minimize the strain which is imparted to said end portions when the central portion 31 of the heddle is twisted. It will readily be seen that if the heddles were left throughout of the full width of 75

the strip from which they are made, considerably more force would be required to effect the twisting of the central portion.

Furthermore, the reduction in the width of the heddles, as shown in Figs. 2 and 3 of the drawings, brings about a considerable reduction in the weight of the harness, which is an additional advantage.

It will of course be readily apparent that as the warp drawing machine acts on the successive heddles, the heddles will be permitted to pass freely from one end of the harness frame to the other, without being obstructed by the supporting devices provided intermediate the ends.

When it is desired to remove the entire set of heddles from the loom, the spring retaining members 16 are released from engagement with the apertures 15 in the ends of the heddle rods 12, whereupon the heddle rods may be shifted longitudinally for a sufficient distance to free the rods at one end of the frame from the slots in the end struts 11, and then slid longitudinally in a reverse direction out of the frame. The rods 12, with the heddles mounted thereon, are thus removable as a unit without necessitating the removal of the intermediate supporting devices from the frame.

In Fig. 4 of the drawings there is shown a modified form of heddle, 30^a, which is adaptable for use where the warp is entered by hand. Heddles of this type may be made in accordance with the method shown in the patent to Fehr, No. 749,724, these heddles being now well known and extensively used.

However, in the present instance, while the warp eye 34^a is of the usual form, the metal on one side of each of the slots 37^a, provided for mounting the heddles on the supporting rods, is cut away at its central portion, as at 38^a, to provide a structure in this type of heddle similar to that shown in Figs. 2 and 3 of the drawings.

Of course, if desired, the heddles may be made with their end portions formed as shown in Figs. 2 and 3 of the drawings, and with their central portions formed as shown in Fig. 4 of the drawings.

The heddles may, if desired, be used on heddle rods 12^a, which are solid in cross-section, as shown in Fig. 8 of the drawings, and provided with supporting means intermediate their ends extending directly from one side thereof instead of employing the auxiliary plate 17 shown in Figs. 1, 5, 6, and 7 of the drawings.

It will of course be apparent that heddles of either of the types shown in the drawings may be individually removed from the rods, or placed thereon, by merely springing the fingers 40 of the end portions 32, and this without removing the rods from the frame. Heddles so constructed may be mounted at any desired place in the frame, for the purpose of replacing broken or damaged heddles.

In Fig. 8 of the drawings there is shown a modified form of heddle supporting rod 12^a, which is made of a solid strip of metal, similar to the strips commonly used in heddle frames, but in this instance the device for supporting the rod intermediate its ends is attached directly thereto, instead of to the slide block 17 shown in Figs. 5, 6, and 7. This form, while not having all the advantageous features of the other form shown, may, however, be used under certain circumstances.

I claim:

1. In a loom harness frame, heddle supporting rods removably mounted therein, each comprising a thin metallic member having internal grooves and a longitudinally extending side opening; and devices for supporting said rods intermediate their ends each comprising a plate positioned in the internal grooves of the rod, a bracket portion secured to said plate and extending through the side opening in the rod, and means for attaching said supporting device to a portion of the frame.

2. In a loom harness frame, heddle supporting rods removably mounted therein, each comprising a member having internal grooves and a longitudinally extending side opening; and devices for supporting said rods intermediate their ends each comprising a plate positioned in the internal grooves of the rod, a bracket portion secured to said plate and extending through the side opening in the rod, and a bolt portion adjustably mounted in a rail of the frame.

3. In a loom harness frame, heddle supporting rods removably mounted therein, each comprising a thin metal member of flattened C shape in cross-section whereby said rod is provided with internal grooves and a longitudinally extending side opening; and devices for supporting said rods intermediate their ends each comprising a plate positioned in the internal grooves of the rod, a bracket portion secured to said plate and extending through the side opening in the rod, and means for attaching said supporting device to a portion of the frame.

4. In a loom harness frame, heddle supporting rods removably mounted therein, each comprising a thin metal member of flattened C shape in cross-section whereby said rod is provided with internal grooves and a longitudinally extending side opening; and devices for supporting said rods intermediate their ends each comprising a plate positioned in the internal grooves of the rod, a bracket portion secured to said plate and extending through the side opening in the rod, and a portion mounted in a rail of the frame.

5. In a loom harness frame, heddle supporting rods removably mounted therein, each comprising a thin metal member of flattened C shape in cross-section whereby said rod is provided with internal grooves and a longitudinally extending side opening; devices for supporting said rods intermediate their ends each comprising a plate positioned in the internal grooves of the rod, a bracket portion secured to said plate and extending through the side opening in the rod, and a bolt portion adjustably mounted in a rail of the frame.

6. In a loom harness, a frame having heddle supporting rods removably mounted therein; said heddle supporting rods comprising thin metal members of flattened C shape in cross-section whereby each of said rods is provided with internal grooves and a longitudinally extending side opening; devices for supporting said rods intermediate their ends, each of said supporting devices including a plate positioned in the internal grooves of the rod, and a bracket portion secured to said plate and extending through the side opening in the rod; and thin flat metal heddles each having a slot at each end for mounting said heddles on the rods, the metal on one side of each slot having an opening to permit the heddles to pass the bracket portions of the supporting devices.

7. In a loom harness, a frame having heddle supporting rods removably mounted therein; said

- 5 heddle supporting rods comprising thin metal members of flattened C shape in cross-section whereby each of said rods is provided with internal grooves and a longitudinally extending side opening; devices for supporting said rods intermediate their ends, each of said supporting devices comprising a plate positioned in the internal grooves of the rod, a bracket portion secured to said plate and extending through the side opening in the rod, and means for attaching said supporting device to a rail of the frame; and thin flat metal heddles each having a slot at each end for mounting said heddles on the rods, the metal on one side of each slot having an opening to permit the heddles to pass the bracket portions of the supporting devices.
- 10 8. In a loom harness, a frame having heddle supporting rods removably mounted therein; said heddle supporting rods comprising thin metal members of flattened C shape in cross-section whereby each of said rods is provided with internal grooves and a longitudinally extending side opening; devices for supporting said rods intermediate their ends, each of said supporting devices comprising a plate positioned in the internal grooves of the rod, a bracket portion secured to said plate and extending through the side opening in the rod, and a portion mounted in a rail of the frame; and thin flat metal heddles each having a slot at each end for mounting said heddles on the rods, the metal on one side of each slot having an opening to permit the heddles to pass the bracket portions of the supporting devices.
- 15 9. In a loom harness, a frame having heddle supporting rods removably mounted therein; said heddle supporting rods comprising thin metal members of flattened C shape in cross-section whereby each of said rods is provided with internal grooves and a longitudinally extending side opening; devices for supporting said rods intermediate their ends, each of said supporting devices comprising a plate positioned in the internal grooves of the rod, a bracket portion secured to said plate and extending through the side opening in the rod, and a bolt portion adjustably mounted in a rail of the frame; and thin flat metal heddles each having a slot at each end for mounting said heddles on the rods, the metal on one side of each slot having an opening to permit the heddles to pass the bracket portions of the supporting devices.
- 20 10. In a loom harness, a frame having heddle supporting rods removably mounted therein; said heddle supporting rods comprising thin metal members of flattened C shape in cross-section whereby each of said rods is provided with internal grooves and a longitudinally extending side opening; devices for supporting said rods intermediate their ends, each of said supporting devices comprising a plate positioned in the internal grooves of the rod, a bracket portion secured to said plate and extending through the side opening in the rod, and a bolt portion adjustably mounted in a rail of the frame; and thin flat metal heddles each having a slot at each end for mounting said heddles on the rods, the metal on one side of each slot having an opening to permit the heddles to pass the bracket portions of the supporting devices.
- 25 11. In a loom harness frame, heddle supporting rods removably mounted therein; means extending from the side of each rod for supporting said rod intermediate its ends; and thin flat metal heddles each having a slot at each end for mounting said heddles on the rods, the metal on one side of each slot having an opening to permit the heddles to pass the means for supporting the rods intermediate their ends.
- 30 12. In a loom harness frame, heddle supporting rods removably mounted therein; means extending from the side of each rod for supporting said rod intermediate its ends; and thin flat metal heddles each having a slot at each end for mounting said heddles on the rods, the metal on one side of each slot having a centrally disposed opening to permit the heddles to pass the means for supporting the rods intermediate their ends.
- 35 13. Loom harness particularly adaptable for having the warp ends entered therein by means of a warp drawing machine without removing the heddles from the frames, said harness including a frame, heddle rods mounted therein, means extending from the sides of the heddle rods for supporting the heddle rods intermediate their ends, and heddles mounted on said rods, each of said heddles being made from a strip of thin flat metal having a slot in each end portion for mounting the heddle on the supporting rods, the metal on one side of each slot having an opening to permit the heddle to pass the means for supporting the rods intermediate their ends, the central portion of each heddle being provided with the usual warp eye, a selector aperture, and a portion adapted to be engaged by the twisting mechanism of the warp drawing machine, the central portion and the two end portions of the heddle being of the full width of the strip and the parts between said central portion and said end portions being reduced in width thereby to minimize the strain on the end portions when the central portion is twisted in the warp drawing machine.
- 40 14. In a loom harness frame, a heddle supporting rod removably mounted therein, and means for supporting said rod intermediate its ends, said means including a plate for engagement with portions of the rod between the upper and lower edges thereof, and a supporting bracket for said plate connected to and extending from a side face of said plate.
- 45 15. In a loom harness frame, heddle supporting rods removably mounted therein; brackets for supporting said rods intermediate their ends, said brackets each having a portion extending sidewise and disposed in a plane between the upper and lower edges of the rod; and thin flat metal heddles each having a slot at each end for mounting said heddles on the rods, the middle of one side of each slot having an opening to permit the heddles to pass the sidewise extending portion of the bracket.

JOHN JACOB KAUFMANN.
